WEFT DETECTOR WITH REMOVABLE
FINGER

Richard G. Turner, Worcester, Mass., assignor to
Crompton & Knowles Loom Works, Worcester,
Mass., a corporation of Massachusetts

Application March 18, 1946, Serial No. 655,102

10 Claims. (Cl. 139—273)

1

This invention relates to improvements in electric weft detectors for looms and it is the general object of the invention to provide an electric weft detector so constructed that the detector fingers can be readily removed for replacement.

Certain types of electric weft detectors employ elongated detector fingers in the form of wires which contact a ferrule on the bobbin being detected at the time of weft exhaustion. As heretofore made the fingers have been mounted on a carrier or the like in such manner that they could not be removed without disturbing the detector and particularly the slide bearings for the fingers. It is an important object of my present invention to provide a weft detector with bearings so constructed that the detector fingers can be deflected laterally because of their resilience to be fitted into and removed from the bearings.

It is another object of my present invention to provide a mounting or base for an electric weft detector provided with open bearing slots which open in different directions so that they effectively hold the detector finger in correct position during normal operation but will permit removal of the finger by manual deflection thereof.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a front elevation of an electric weft detector made according to my present invention.

Fig. 2 is a front elevation looking in the direction of arrow 2, Fig. 1.

Fig. 3 is a plan view of the detector looking in the direction of arrow 3, Fig. 1.

Fig. 4 is a transverse vertical section on line 4—4 of Fig. 1.

Fig. 5 is a detailed vertical section on line 5—5 of Fig. 1.

Fig. 6 is a perspective view of the base forming part of the electric weft detector, one part of the base being shown spaced from the other part in the position it assumes during assembly, and

Fig. 7 is a diagrammatic view showing the manner in which the detector fingers can be deflected for application to or removal from the base.

Referring particularly to Fig. 1, I have shown a support 10 which is mounted on the loom and may be either stationary or moved away from the lay at the time of a weft replenishing operation. The bobbin B is provided with a metallic ferrule F which is normally covered with weft,

2

but as weft exhaustion approaches the ferrule is uncovered so that it can electrically connect two detector fingers 11 and 12. These fingers are preferably metallic and are similar to detector fingers heretofore used, being made of steel and sufficiently resilient to permit a considerable amount of bending or deflection without taking a permanent set. Each detector finger has a small collar or shoulder 13 rigid with respect thereto and may have a bobbin engaging tip 14.

The base on which the detector fingers are mounted comprises a lower part 20 and an upper part 21 both of which are preferably made of insulating material, such as fiber, plastic, or a phenol-condensation product. The bottom part 20 has a forward body 22 having lateral extensions 23 perforated as at 24 to receive bolts 25 passing through the support 10. Extending rearwardly from the body 22 is an arm 26 having a rear head 27 provided with laterally spaced upwardly opening bearing slots 28 and 29 located respectively at the right and left of the head 27 as viewed in Figs. 2, 5 and 6. A second head 30 extending forwardly from the body 22 is provided with similar upwardly opening bearing slots 31 and 32 located respectively at the right and left of the detector. Slots 28 and 31 are vertically aligned, as are also slots 29 and 32, and their bottoms are horizontally aligned 30 and rounded to provide a substantial sliding bearing surface for the fingers 11 and 12.

The second or upper part 21 of the detector base has a body 35 provided with right and left integral arms 36 and 37, respectively, formed with horizontally opening right and left bearing slots 38 and 39, respectively. The body 35 has a pair of holes 40 extending vertically therethrough to receive screws 41 which are tapped into holes 42 in the bottom member 20. When the base 40 is assembled the upper part 21 will be resting on top of the body 22 and arm 26 and will be held firmly in position by the screws 41 with the bottom or inner end of slot 38 aligned with the bottoms of slot 28 and 31. These three slots 45 form a group of bearings for detector finger 11. Similarly, the bottom of slot 39 is aligned with the bottoms of slots 29 and 32 to form a group of bearings for fingers 12. As shown particularly in Fig. 6 slot 38 lies between a relatively short top projection 45 of arm 36 overhanging a longer bottom projection 46. A similar construction is used for the slot 39.

The front head 30 may be provided with a horizontal rib 50 and has a front wall 51 provided with screw holes 52 to receive attaching

screws 53. These screws hold the forward broad ends 55 of sheet metal springs 56 against the wall 51 and may also hold the terminals of wires 57 in position. These wires are connected to an external loom controlling detecting circuit not shown.

The springs 56 are bowed downwardly and then upwardly at their rear ends and are perforated at 58 to receive the fingers 11 and 12 at points between rear head 27 and the intermediate bearing part 21. The rear free ends of the springs are narrower than are their front ends and bear against the shoulders 13 for the purpose of holding the detector fingers rearwardly but yieldingly in detecting position for engagement with the bobbin B during detecting operations of the loom.

When assembling the detector, the wires or fingers 11 and 12 can be inserted in their respective slots 38 and 39 of the top support part 21 and then lowered from the position indicated in Fig. 6 to that shown for instance in Fig. 2. During the lowering operation the detectors will fall into their corresponding slots in the front and back heads 30 and 27, after which the screws 41 will secure the top part 20 to the bottom part 21. After this assembly is made it will not be necessary to remove the top part 21 and for certain features of my invention the top part could be made integral with the lower part.

During operation, the fingers 11 and 12 will be moved forwardly in their bearing slots at each period of weft detection and when the ferrule F is uncovered it will electrically connect the fingers so that the wires 57 will be connected for the purpose of closing the aforesaid loom controlling circuit not shown.

If for any reason one or the other of the feeler fingers 11 or 12 should become damaged and require removal this can be effected merely by bending the intermediate part of the finger laterally so that said intermediate part can move out of the associated slot 38 or 39, and up over the short projection 45, after which the finger can be removed from its slots in the front and back heads. When replacing with a new finger the procedure may be as indicated in Fig. 7, the new finger being placed as indicated at I in the corresponding slots of the front and back heads and resting on the short projection 45. The new detector is then bent laterally as indicated at II until it passes under the projection 45 and snaps into the horizontal open slot to assume the straight position shown at III. It is to be understood that when a new finger is applied to the detector its forward end, the end at the left in Fig. 1, will be passed through the perforations in the narrow free end of the associated spring 56 prior to fitting to the base. When the damaged finger is removed it will be slipped out of the spring perforations 58, and when the new finger is to be applied it will first be fitted through the perforation.

Having thus described my invention it will be seen that changes and modifications may be made therein by those skilled in the art without departing from the spirit and scope of the invention and I do not wish to be limited to the details herein disclosed, but what I claim is:

1. In an electric weft detector having two spaced resilient detector fingers, a base made of electric insulating material and having formed therein for each finger three open bearing slots one of which is between the other two, said one bearing slot opening in a direction different from

the direction of opening of the other two bearing slots, each finger extending through and guided by its three bearing slots, the intermediate part of each finger due to resilience thereof being deflectable in the direction in which said one bearing corresponding thereto opens for removal therefrom and then being removable from its other two bearings.

2. In an electric weft detector for looms, a base made of electric insulating material and having two groups of three spaced opening slot bearings one of which in each group opens in a direction different from the direction of opening of the other two bearing slots of the group, and two elongated resilient electric detector members each extending through and guided by and normally held in position by the bearings of the corresponding group, each detector member due to the resilience thereof being deflectable laterally for removal from one of said open slot bearings corresponding thereto to enable said detector member to be thereafter removed from the remainder of bearings corresponding thereto.

3. In an electric weft detector having a pair of elongated electric detector fingers, a base made of electric insulating material and having for each finger open slot bearing means one part of which is between two other parts of the bearing means, said one part opening in a direction different from the direction of opening of at least one of the other of said parts, each finger being resilient and normally held in position by and slidable relatively to the open slot bearing means corresponding thereto but deflectable laterally due to the resilience thereof for removal from the corresponding one bearing part to enable subsequent removal from the other corresponding bearing parts.

4. In an electric weft detector mechanism having a pair of elongated electric detector fingers, a base made of electric insulating material and having for each finger front and back open slot bearings between which is located an intermediate open slot bearing, said front and back bearings for each finger opening in substantially the same direction and the corresponding intermediate bearing opening in a different direction, each finger being resilient and normally located in the corresponding bearings and held in position thereby and slidable relatively thereto, each finger due to the resilience thereof being deflectable laterally for removal from its intermediate bearing and being thereafter removable from its front and back bearings.

5. In an electric weft detector mechanism having a pair of elongated electric detector fingers, a base made of electric insulating material and having for each finger front and back open slot bearings between which is located an intermediate open slot bearing, said front and back bearings for each finger opening substantially vertically and the corresponding intermediate bearing opening substantially horizontally, each finger being resilient and normally located in the corresponding bearings and held in position thereby and slidable relatively thereto, each finger due to the resilience thereof being deflectable laterally for removal from its intermediate bearing and being thereafter removable from its front and back bearings.

6. In an electric weft detector mechanism having a pair of elongated electric detector fingers, a base made of electric insulating material and having for each finger end open slot bearing means and also intermediate open slot bearing

means, one of said bearing means for each finger opening vertically and the other bearing means therefor opening horizontally, each finger being resilient and normally located in and guided by the corresponding bearing means, said finger due to resilience thereof being deflectable for movement out of one of said bearing means therefor and being thereafter removable from the other bearing means therefor.

7. In an electric weft detector having a pair of elongated electric detector fingers, a base made of electric insulating material and having formed therein for each finger three open bearing slots one of which is between the other two, said one bearing slot for each finger opening in a direction different from the direction of opening of the other two corresponding bearing slots, each detector finger being resilient and extending through the corresponding slots and normally held therein, and a spring for each finger supported by said base and having an end thereof in engagement with the corresponding finger between said one bearing slot therefor and one of the other bearing slots therefor, the intermediate part of each finger due to the resilience thereof being deflectable laterally for removal from its one bearing slot while in engagement with said spring and being thereafter removable from its other bearing slots.

8. In an electric weft detector having a pair of elongated electric detector fingers, a base made of electric insulating material and having formed therein for each finger three open bearing slots one of which is between the other two, said one bearing slot for each finger opening in a direction different from the direction of opening of the other two corresponding bearing slots, each detector finger being resilient and extending through its slots and normally held therein, and a spring for each finger supported by the corresponding base and having one end thereof perforated to receive said finger at a point between the corresponding one bearing slot and one of the other associated bearing slots, the intermediate part of each finger due to the resilience thereof being deflectable laterally for movement out

of its one bearing slot while extending through the spring therefor and being thereafter removable from its other bearing slots and from the corresponding spring.

9. In an electric weft detector having two normally straight resilient detector fingers, a base made of electric insulating material and having formed therein for each finger three open bearing slots the bottoms of which are in alignment, one of said bearing slots for each finger being between the other two bearing slots and opening in a direction different from the direction of opening of the other two corresponding bearing slots, each detector finger engaging the bottoms of the corresponding bearing slots and normally held therein, that part of the finger in the one bearing slot corresponding thereto due to the resilience of the finger being deflectable laterally for removal from its one bearing slot and then returning to a straight form and being thereafter removable from its other bearing slots.

10. In an electric weft detector having two normally straight resilient detector fingers, a base made of electric insulating material and having for each finger open slot bearing means, each detector finger normally located in the corresponding open slot bearing means, each bearing means being so constructed as to prevent removal of the corresponding finger by a motion lateral thereof so long as the finger is straight, said bearing means for each finger being so constructed that the finger when deflected laterally due to the resilience thereof can be removed from its bearing means.
